UNITED STATES PATENT OFFICE.

JOHN R. LONG, OF AKRON, OHIO.

BENCH-VISE.

1,218,788.

Specification of Letters Patent.

Patented Mar. 13, 1917.

Application filed June 4, 1915. Serial No. 32,101.

To all whom it may concern:

Be it known that I, JOHN R. LONG, a citizen of the United States, residing at Akron, in the county of Summit and State of Ohio, 5 have invented certain new and useful Improvements in Bench-Vises, of which the following is a specification.

The invention herein relates to a double swivel automatic bench vise, and is an improvement on the construction shown in my 10 Patent No. 742,096, issued October 20, 1903.

In the accompanying drawings, Figure 1 is a side elevation of the vise and Fig. 2 is a front end elevation thereof. Fig. 3 is 15 a rear end elevation. Fig. 4 is a longitudinal sectional elevation. Fig. 5 is a plan view on line 5—5, Fig. 4. Fig. 6 is an outside view of the clamping cap or disk on the rear end of the vise. Fig. 7 is a perspective of the sleeve nut for the operating screw.

The parts on which I especially desire protection in this application are the new construction of the base B, the yoke members m and m', the key k, the nut n and the parts operatively associated and combined therewith.

Thus, the base B as shown herein has an annular vertically walled channel about a 30 central hub h, which has a flat top surface on a plane with the outer wall of the base about said channel, and the two jaw supporting yokes m and m' have semi-circular extensions 2 at their bottom rotatably seated in said channel but otherwise fitting rather snugly therein. Each yoke or yoke member is further provided with lateral shoulders seated upon the outer wall of the base about said channel and lapping approximately half way across the top of hub h at the inside, as seen at 3. This latter feature of a bearing on the hub is important because it forms something of a fulcrum for the said yoke members when said 45 members are drawn toward each other at the top to tighten the same on the jaws as will presently appear.

The movable jaw J has a tubular spindle

or extension 4, and the inner or so-called fixed or stationary jaw has a tubular extension or body 5 into which the spindle 4 is projected or telescoped nearly its entire length, and the said fixed or stationary jaw J' is mounted in openings or bearings in the two yokes or yoke members m and m' and rotatably locked therein as will presently be seen.

The operating or working screw s for the jaws is projected lengthwise through both ends of the outer jaw J and provided with a fixed flanged head 6 at its front and constructed to engage a wrench or crank handle thereon, and at its opposite end extends through a sleeve nut n having a screw thread operatively engaged by said screw. 60 The said nut becomes a fixed member and is peculiar to the present organization of vise in that it has a collar 7 about its outer portion adapted to engage against the inner otherwise closed end 8 of the fixed jaw J' 70 and a square or angular shank 9 next outside said end 8 and a screw-threaded extremity 10 outside said shank. The square shank 9 fits closely in a correspondingly shaped hole through the end 8 of the inner 75 jaw extension, so that it is locked against rotation therein, and the cap c has an opening or hole of like shape, Fig. 6, and fits comfortably on said shank. The said shank terminates with the said cap outside, and 80 an octagonal or like shaped nut 12 is engaged over the threaded end 10 of said sleeve nut and bears against the cap c, forcing the same against the outer edge of the yoke member m' and at the same time 85 drawing the inner enlargement of the collar 7 tight against the head 8 of the fixed jaw.

The said nut 12 is usually adapted to be rotated by hand so that a tool is not needed for this purpose. This construction not only eliminates the screws 2 in the patent above referred to but it equalizes the pressure of the friction cap or plate against the rear yoke member m', whereas in the old construction the screws 2 could not be depended upon because they would work loose.

on one side and remain tight on the other with the result that the friction plate had a pinching action when the jaws were revolved.

5 By building the base B with a hub h, and annular channel about the same as shown, a greatly improved grip of the parts is obtained over the old construction with less tightening exertion because the pressure between the two yokes m and m' is thrown against the sides and top of the hub when the said parts are compressed or frictionally tightened, thus producing a terrific grip on the base, whereas in the old construction the middle pressure was wasted.

The movable jaw J is adapted to be moved back and forth for work within limits by means of a flat sided key k through the body 20 of the outer jaw and which runs in the key-way or spline 15 in said jaw. By using a key of this kind and stopping the key-way short of the end of jaw extension 4 I prevent the withdrawal of the movable vise 25 screw from backing out of the threaded end of the sleeve nut n. In the old construction it was necessary to mill the key-way or spline the entire length of the movable jaw and have it open at the end in order to assemble the parts, and in addition the old 30 key was a very difficult and expensive article to deal with, whereas in the present construction it requires only half the work and is easily accomplished and the movable jaw is 35 limited in and by said key-way.

The entire vise shown is made of cast steel and the jaws are of ribbed design and provided with jaw plates 18 in the bite thereof which are attached by hollow headed 40 screws 20. The said heads being on the outside of the jaws the plates 18 are not weakened as in the old construction in which the heads are inside and are sunk into the plates flush with the surface, thus greatly 45 weakening the plates. By the present construction I am enabled to use a hollow headed screw which affords opportunity to tighten the same so that it will not work loose, it being possible to insert the jaw plates and 50 then compress the jaws together by means of the main screw s and then insert the plate screws from without and get a tighter fit than was possible before.

A bushing 22 fixed in the outer jaw serves 55 as bearing for the operating screw s, and a collar 23 is fixed on said screw next within said bushing and serves to confine the screw in working relations. The pressure of the head 6 of the screw is directly against the 60 jaw itself.

The foregoing construction provides for the locking of the vise as to all its swivel movements by or through the yoke or yoke

members m and m' and the axial rotation of the two jaws together.

65

What I claim is:

1. In bench vises as described, a base having a centrally disposed hub and an annular channel about said hub, and a pair of jaw-supporting members having segmentally 70 curved portions seated in said channel and upon said base about said channel.

2. A bench vise comprising a base having an annular channel with substantially parallel vertical side walls, in combination with 75 jaw supporting members seated on said base and provided with segmental portions occupying said channel and openings in their top portions, and jaws mounted in said openings.

3. A bench vise as described having a base 80 with an annular channel, in combination with two jaw supporting members having each a semi-circular bottom portion extending into said channel and provided with shoulders on their inside lapped upon the 85 middle portion of said base, jaws in said members and means therewith to lock said members in said channels.

4. A bench vise having a base with an annular channel, a pair of jaw supports having substantially semi-circular extensions occupying said channel and provided with shoulders partially overlapping the middle of said base, jaws confined in said supports and means therewith adapted to force said 95 supports into frictional engagement with the walls of said channel.

5. In a bench vise, the construction described comprising a pair of supports and a base in which said supports are rotatably mounted, a pair of jaws having tubular extensions mounted within said supports, an operating screw and a nut-sleeve therefor provided with an angular shank mounted in a correspondingly shaped hole in the end of the outer of said jaw extensions, a cap with an angular hole mounted on said shank and a nut bearing against said cap to tighten the same.

6. A bench vise constructed as described 110 and having an operating screw, a sleeve-nut in which said screw engages having a square shank and a collar at the inner portion of said shank and a screw threaded outer end, a jaw extension in which said shank is engaged, a cap mounted on said shank and a nut constructed to be gripped by the hand and engaged on said threaded outer end to tighten said cap.

7. In a bench vise, the construction described having an operating screw and a sleeve-nut therefor provided with an angular shank, an inner jaw having an angular hole in its end to receive said shank and a collar on said nut bearing against the inside 125 of said end, a tightening cap mounted on

said shank and a nut on said sleeve-nut bearing against said cap.

8. A bench vise comprising a fixed and a movable jaw provided each with a tubular extension sleeved one within the other, the inner of said extensions having a key-way terminating within the end thereof, a key free in said way, a hole in the outer of said extensions opposite said key-way and adapt-

ed to enter said key through the same and 10 a plug removably closing said hole.

In testimony whereof I affix my signature in presence of two witnesses.

JOHN R. LONG.
